UNITED STATES PATENT OFFICE.

DAVID L. ALEXANDER, OF CHEVY CHASE, MARYLAND.

INDUCTION REGULATOR.

Application filed October 2, 1926. Serial No. 139,130.

The invention relates to an induction regulator controlling the flowing of alternating currents.

The object of the present invention is to improve the construction of induction regulators and to provide a simple, practical and efficient device of strong, durable and inexpensive construction adapted to be easily wound and readily assembled.

A further object of the invention is to provide an induction regulator adapted to afford a completely closed magnetic circuit at all times to prevent loss of current and capable of gradually varying the induced current from maximum to minimum and vice versa.

A further object of the invention is to provide an induction regulator equipped with a movable core member provided with means of gradually increasing capacity to form separate paths for the magnetic flux around the core of the secondary winding in varying the strength of the induced current from maximum to minimum and to establish an air gap in such separate paths to prevent the flow of the magnetic flux through the said separate paths and cause all of the flux to flow through the core of the secondary winding when the induction regulator is operating at maximum inductance.

With these and other objects in view the invention consists in the construction and novel combination and arrangement of parts hereinafter fully described illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings, in which like characters of reference designate corresponding parts in the several views:

Fig. 1 is an elevation of an induction regulator constructed in accordance with this invention and shown arranged for affording an induced current of maximum strength.

Fig. 2 is an end elevation of the same.

Fig. 3 is a transverse sectional view on the line 3—3 of Fig. 1, the parts being arranged as shown in that figure.

In the accompanying drawing in which is illustrated the preferred embodiment of the invention, the induction regulator comprises in its construction a fixed core member 1,

having a primary winding 2 and a movable core member 3 carrying a secondary winding 4. The fixed core member is preferably of laminated structure and is composed of spaced side portions 5 and a connecting transverse end portion 6 on which the primary winding 2 is mounted, but the winding may be arranged in any other desired

manner and may, as will be readily understood, be reversed with respect to the movable and fixed core members. The movable core member consists of a straight laminated bar or core and a laminated rim secured to the ends of the core and surrounding the

same as clearly illustrated in Fig. 1. The straight bar or body of the movable core member is arranged diametrically with relation to the rim or peripheral portion which is divided by diagonal slots 7 into separate overlapping sections 8.

The straight laminated bar is wound before it is assembled in the parallel rim and after being wound it is pressed into the rim which is provided at diametrically opposite points with substantially dovetailed recesses 9 for the reception of dovetailed ends 9a of the straight bar or body portion of the movable core member.

This securely interlocks and fastens the straight bar and the rim together and after they have been assembled in this manner, the rim is split diagonally as illustrated in Fig. 2 of the drawing at opposite sides of the straight body portion of the movable core member to provide similar

overlapping tapered ends for the sections 8 of the rim. The slot or cut made in the rim is of a length less than the width of the space between the sides or portions 5 of the fixed core member so that when the movable core member is arranged as shown in Fig.

1 of the drawing with its straight core portion in parallelism with the transverse end portion 6 of the fixed core member with the primary and secondary windings in par-

allelism to afford an induced current of maximum strength, the upper and lower portions of the rim will present air gaps at the slots or cuts 7, and will prevent the magnetic

flux from flowing through the upper and lower portions of the rim and cause all of the fluxes to flow through the straight body portion of the movable core member and af-

ford a maximum efficiency with minimum loss or leakage of the magnetic flux through the upper and lower portions of the rim.

As soon as the movable core member which

110

is mounted to turn on a central pivot or axis 10 is partially rotated, one of the tapered ends of the lower portion of the rim will be carried into contact with the other side portion 5 of the fixed core member. These overlapping end portions 8 of the sections of the rim taper circumferentially and provide portions of gradually varying capacity for contact with the sides of the fixed member 10 to provide separate paths at opposite sides of the body portion of the movable member for the magnetic flux of the magnetic circuit formed by the fixed and movable core members. The magnetic flux is thus caused to 15 divide at opposite sides of the straight body portion and portions of the flux will pass through the straight body portion and through the upper and lower portions of the rim and there will be a gradual reduction 20 of the flux through the straight body portion and a gradual reduction in the strength of the induced current. By this construction, there is no sudden diminution or increase in the strength of the induced current and the induced current may 25 be varied from maximum to minimum in this gradual manner and when the movable core member is rotated to a position at 90° to that in which it is illustrated in Fig. 1 of the drawing, the secondary winding will be 30 arranged at right angles to the primary winding and there will be no flow of current through the secondary winding and no loss of current through leakage of magnetic flux. 35 The spaced side portions of the fixed core member are provided with concave bearing faces 11, which conform to the configuration of the outer peripheral bearing face of the rim and it will be apparent that there 40 is contact at all times between the movable core member and the spaced side portions of the fixed core member to provide at all times a closed magnetic circuit, and that the slots or cuts 7 are arranged to form air 45 gaps in the side portions of the rim to prevent the magnetic flux from flowing through such side portions when the induction regulator is arranged to operate at maximum efficiency. 50 The movable core member has mounted on its pivot or shaft 10, a worm wheel 12 which meshes with the worm 13 of a shaft 14 provided with a crank handle 15 or other suitable means for rotating the shaft 14 to 55 adjust the rotary core member. The shaft 14 is mounted in suitable bearings 16 and the worm gear will operate to firmly hold the movable core member in its adjustment and resist any tendency of the movable core member 60 to rotate under the action of the primary current. The shafts and gearing for adjusting the movable core member are designed to be made of bronze, brass or other non-magnetic material. The leads or wires 17 and 18 of 65 the primary winding are connected with a

suitable source of current supply and the wires 19 and 20 of the secondary winding carry the load in the arrangement shown in Fig. 1, but in addition to the reversing position of the primary and secondary windings, the primary winding may take the form of any other well known arrangement in this class of devices. 70

The shaft 10 on which the movable core member 3 is mounted is journaled in suitable bearings of side plates 21 riveted or otherwise secured to the opposite faces of the spaced side portions 5 of the fixed core member. The movable core member is arranged between the side plates 21 which with the shaft 14 are designed to be constructed of bronze or other suitable non-magnetic material so that neither the side plates nor the gearing will afford a path for the magnetic flux and interfere with the operation of the 80 device. 75

What is claimed is:

1. An induction regulator including a magnetic circuit consisting of a fixed core member having spaced sides and carrying a 90 winding a movable member having a peripheral portion contacting with the spaced sides in each adjustment of the movable core member to provide a completely closed magnetic circuit of approximately the same cross 95 section at all times, and a diametrically arranged member carrying a winding. 100

2. An induction regulator including a fixed core member having spaced sides, a 105 movable core member composed of a substantially straight body portion and a rim contacting with the sides of the fixed core member, said straight portion being arranged diametrically with relation to the rim and the latter maintaining a constantly 110 closed magnetic circuit between the fixed and movable members, and primary and secondary windings on the said members. 105

3. An induction regulator including a fixed core member having spaced sides, a 110 movable core member composed of a substantially straight body portion and a rim contacting with the sides of the fixed core member, said straight portion being arranged diametrically with relation to the rim and the latter maintaining a constantly 115 closed magnetic circuit between the fixed and movable members, said rim being split to form an air gap located between the side portions of the fixed core member when the regulator is operating at maximum efficiency, and primary and secondary windings on the said core members. 120

4. An induction regulator including a 125 fixed core member having spaced sides, a movable core member composed of a substantially straight body portion and a rim contacting with the sides of the fixed core member, said straight portion being arranged diametrically with relation to the 130

rim and the latter maintaining a constantly closed magnetic circuit between the fixed and movable members, said rim being split diagonally to provide correspondingly tapered overlapped portions arranged to form an air gap, and primary and secondary windings on the said core members.

5. An induction regulator including a fixed core member having spaced sides, a movable core member composed of a substantially straight body portion and a rim contacting with the sides of the fixed core member, said straight portion being arranged diametrically with relation to the rim and the latter maintaining a constantly closed magnetic circuit between the fixed and movable members, said rim being provided at opposite sides of the straight portion with diagonal cuts forming air gaps, said cuts being of a length less than the space between the side portions of the fixed core member, and primary and secondary windings on the said core members.

6. An induction regulator including a magnetic circuit consisting of a fixed core

member having spaced sides and a movable core member composed of a circular rim and a straight bar arranged diametrically with relation to the rim, said rim contacting with the spaced portions and split at opposite sides of the straight portion to provide air gaps when the device is operating at maximum efficiency, said straight portion having its ends interlocked with the rim.

7. An induction regulator including a magnetic circuit containing a fixed core member having spaced sides, a movable core comprising an annular member and a diametrically arranged connecting member, said annular member having opposite peripheral portions arranged to contact with the spaced sides of the fixed core member for providing separate paths for the magnetic flux, and primary and secondary windings on the core members, the winding on the movable core member being located between the said peripheral portions.

In testimony whereof I have hereunto set my hand.

DAVID L. ALEXANDER.
